ELECTRIC LAMP SOCKET

Henry J. McCarthy, Danvers, Mass., assignor to
 Hygrade Sylvania Corporation, Salem, Mass.,
 a corporation of Massachusetts

Application June 12, 1940, Serial No. 340,083

2 Claims. (Cl. 173—328)

My invention relates to a socket for electric lamps and more particularly to a socket for electric gaseous discharge lamps of the tubular type.

5 An object of my invention is to provide a socket so constructed as to permit a quick and easy insertion of the lamp therein.

Another object is to provide a socket so constructed as to create a positive locking position 10 when the lamps are inserted therein.

A further object is to provide a socket for electric gaseous discharge lamps in which the contact terminals of said lamp are concealed thereby eliminating the possibility of short-circuiting 15 and shock.

Still another object is to provide a socket so designed in its structure that it will obviate any possibility of pins on opposite sides of the lamp from being inserted accidentally in the wrong 20 slot and thereby placing a strain on the pins and the base itself.

Further objects and advantages will be apparent from the accompanying specification and drawings in which:

25 Figure 1 is a perspective view of the cover plate.
 Figure 2 is a rear elevational view of the socket with the base in the locking position.

Figure 3 is a rear elevational view of the socket with the base being sprung out of the socket.

30 Figure 4 is a front perspective view of the base member.

Figure 5 is a rear elevational view of the base member showing the spring contact members in position.

35 Figure 6 is a bottom view of the base member.
 Figure 7 is a top view of the base member.

Figure 8 is a rear perspective view of the base member.

Figure 9 is a side view of a lamp disposed in 40 the correct position for its proper insertion into the sockets.

Figure 10 is a front view of the socket.

Similar reference characters refer to similar parts throughout the several views of the drawings 45 and in the specification which follows.

The socket according to my invention comprises two pieces of insulating material, one of which is a cover plate, 1, and the other a base member 2. The base is recessed to provide channels in which the spring contact members 3 and 4 are seated. The cut-out 5 provides a passage through which the pins 6 and 7 on the lamp base 8 may pass and the cut-outs 9 and 10 provide a locking position into which the pins 6 and 7 are rotated.

The upper section of the inner face of the socket has the arcuate cut-out 5 to provide for the rotation therein of the pins 6 and 7 of the lamp base 8 to a contact in the cut-out locking ears 9 and 10, with the spring contact members 3 5 and 4. The top of the face has a slot 11 therein, of a size and shape to permit the insertion therethrough of the base pins 6 and 7 when said pins are in alignment with this slot. The cut-out 5 diverges downwardly from the slot 11, broadening 10 out in an arcuate manner and having a pair of cut-out locking ears 9 and 10 adjoining thereto at right angles to the lower extremity of the arcuate portion.

Thus to insert a lamp-base in the socket, the 15 base is first placed in such a position that the base pins are in alignment with the slot 11 at the top of the socket. By a straight downward movement the pin 6 will slide down through the slot 11 and into the cut-out 5, and by rotating 20 the lamp in a clock-wise manner, the pin 6 which was inserted into the top slot 11 first, will move into the locking position 9 adjoining the cut-out 5. By rotating the base, using the pin already 25 in the locking position 9 as the center of rotation, the other pin 7 will slide along through the cut-out 5 and into the other locking position 10.

These locking ears 9 and 10 are shaped in such a manner that they are narrowed down at the point where they adjoin the arcuate cut-out 5 so 30 as to be just about wide enough to allow the passage of the base pins therethrough. The spring contact fingers 3 and 4 are so shaped at their upper extremities, i. e., at that portion of the fingers which projects into the arcuate cut-outs 5, that they establish contact with the base pins when the pins are ready to move into the locking ears 9 and 10.

When, in the process of inserting a base into its socket, the base takes a position similar to 40 that shown in Figure 3, pressure is applied to the base to cause the spring contact finger 3 to flex backward sufficiently to allow the base pin 6 to enter the locking cut-out 9. When the pin 6 is in its locking position in the cut-out 9, the base 45 is rotated to bring the pin 7 down through the arcuate cut-out 5 and into contact with the spring contact member 4. By applying pressure on the base so that the pin 7 will exert a force against the spring contact finger 4, the finger 50 will flex sufficiently to allow the pin 7 to enter the locking cut-out 10. The pins are firmly locked in these cut-outs 9 and 10 because the spring contact members 3 and 4 are so shaped 55 at the point where they contact the base pins 55

that they exert an upward pressure on the pins, thus forcing the pins up against that side of the locking position which forms a right angle with the sides of the arcuate cut-out 5. Thus the pressure exerted by the contact fingers really forces a positive locking as shown in Figure 2.

The lobes 12 and 13 form a part of the spring contact fingers 3 and 4 and are located at the tip of the contact members in their extension into the locking cut-outs 8 and 10. These lobes serve as a means of preventing the lamp pins from slipping down inside the contact fingers into that section of the locking cut-outs which is located behind the contact fingers. If this possibility were not provided for, the lamp might be inserted into the sockets in such a manner that a pin might slide over the tip of a contact finger and become locked behind it in the locking cut-out. Any force exerted on the lamp to remove it from this incorrect position would tend to loosen or break the base pin.

When the base is to be removed from the socket, there is no danger of twisting or straining the pins because the base may be rotated in either a clock-wise or counter-clock-wise direction. In either case, a pin will be released from its locking position by the rotating motion and will slide up into the arcuate cut-out section 5 and assume a position similar to that shown in Figure 3. With the pin, 7, now free from any pressure, the pressure exerted by the other spring contact on the other pin 6 will be released in an upward direction when the pin 7 which was first released reaches the cut-out 11. Thus the sudden release of pressure on the pin 6 will cause the base to snap out of the socket. By taking advantage of this force exerted by the release of pressure on the spring finger, the danger of an improper withdrawal of the base from the socket is thereby obviated.

The two channels for the spring contact members 3 and 4 are recessed down through the center of the base member of the socket extending downwardly from the cut-out locking ears so as to provide positions in which the spring fingers may be mounted. These channels are so shaped that they diverge upwardly into the cut-out locking ears so as to provide for the flexing of the spring contact members when the base pins are inserted therebetween.

These channels broaden out at their lower extremity and the recesses 14 and 15 are provided for the mounting of the screw plates 16 and 17 on the bottom of the spring contact members 3 and 4. These contact members may be bent at right angles at their lower extremities so as to

provide for the mounting thereon of the screw plates. Lead-in wires may be connected to the screw-plates 16 and 17 through the cut-outs 18 and 19, thereby establishing an electrical contact with the socket contact members 3 and 4.

The cover plate 1, is fastened to the base 2 by means of screws or the like driven into the studs 20 and 21 provided therefor in the base member of the socket. The stud 22 in the middle of the upper part of the cover plate projects through the arcuate cut-out of the base member when the cover plate is attached, in a flush mounting manner, to the base member. This stud serves as a safety device in helping eliminate any possibility of shock from contact with the fingers extending up through the cut-out locking ears.

What I claim is:

1. A socket for electric lamps and similar devices having bases with two contact pins, said socket comprising: a hollow insulating member 20 with a broad face and small thickness perpendicular to the face, said face having a cut-out portion principally bounded by three intersecting arcs with ear-shaped cut-out portions at each end of the arc forming the base of the main cut-out portion and with the intersection of the other two arcs being at and in communication with a transverse slot in the top of the hollow insulating member; two flat spring contact pieces inside the hollow insulating member, one of said spring contact pieces being set behind each of the eared cut-out portions of the hollow insulating member, each of said spring members being placed at an angle to the longitudinal axis of the main insulating member to exert a force upward from the base of the main insulating member and toward the longitudinal axis of said member.

2. A socket for electric lamps and similar devices having bases with two contact pins, said socket comprising: a hollow insulating member 40 with a broad face and small thickness perpendicular to the face, said face having a cut-out portion in the shape of a three-sided figure having its apex in communication with a transverse slot in the top of the hollow insulating member; two flat spring contact pieces inside the hollow insulating member, one of said spring contact members being set behind each of the base corners of the three sided cut-out portion; each of said spring members being placed at an angle to the longitudinal axis of the main insulating member to exert a force upward from the base of the main insulating member and toward the longitudinal axis of said member.

HENRY J. McCARTHY.
